UNITED STATES PATENT OFFICE.

DAVID M. McCATHIE, WESLEY R. CAIN, AND NAPOLEON B. CAIN, OF PORT JERVIS, NEW YORK, ASSIGNORS TO THE MOMENTUM REGULATOR, INC.

FIRE-ESCAPE.

No. 820,241.

Specification of Letters Patent.

Patented May 8, 1906.

Application filed August 10, 1905. Serial No. 273,648.

To all whom it may concern:

Be it known that we, DAVID M. McCATHIE, WESLEY R. CAIN, and NAPOLEON B. CAIN, citizens of the United States, residing at Port Jervis, in the county of Orange and State of New York, have invented certain new and useful Improvements in Fire-Escapes; and we do declare the following to be a full, clear, and exact description of the invention, such as will enable others skilled in the art to which it appertains to make and use the same.

Our invention relates to improvements in that class of fire-escapes in which a chain or rope is employed for lowering a person to the ground, the same being passed through a drum or casing secured to the wall of a building or to some fixed object in an apartment of the same and operating an automatic brake mechanism, whereby the descent of the person is regulated.

The object of our invention is to improve and simplify the construction and operation of devices of this character, and thereby render the same more efficient and durable in use and less expensive to manufacture.

The above and other objects are attained by means of the construction illustrated in the accompanying drawings, in which—

Figure 1 is a front view of a portion of a building, showing our improved fire-escape arranged in position for operation. Fig. 2 is a vertical sectional view through the device. Fig. 3 is a horizontal sectional view on the plane indicated by the line 3 3 in Fig. 2. Fig. 4 is a detail perspective view of the weight, and Fig. 5 is a detail view showing a modified form of guide and friction device for the chain.

Referring to the drawings by numerals, 1 denotes the casing, in which the operating parts of our fire-escape are mainly inclosed and which, as shown, is of substantially cylindrical form, consisting of a base 2 and a cover 3. These parts are connected by bolts 4, and the base 2 may be secured upon a wall or other stationary object in any suitable manner.

Mounted in bearings formed concentrically in the circular portions of the base and cover is a shaft 5, upon which is secured a sprocket-wheel 6. Passing over the sprocket-wheel 6 is a chain 7, which has its ends extending downwardly through guides 8, which are preferably formed integral upon

the base 2 of the casing. These guides extend vertically and have their upper and lower ends 9 curved outwardly and their central portions 10 also curved outwardly at opposite points to form chain-passages between them and a friction-surface 11, which is in the form of a projection, provided upon the base 2 between the guides 8 and comprising a substantially circular upper portion 12 and a straight lower portion 13. As clearly shown in Fig. 2 of the drawings, the chain 7 passes downwardly through the curved passages between the guides 8 and the friction block or projection 11, so that it engages the opposite faces of its circular portion 12 and is resisted in its passage by such frictional engagement. The portions of the guides 8 which project beyond the cover 3 are preferably covered by a plate 14, and the ends of the chain 7 project out of the casing beneath this plate, as shown in Fig. 2. Upon each end of the chain is attached a belt 15, adapted for attachment to the body of a person to be lowered from a building, the chain being of such length that when one person descends the belt upon the other end of the chain will be elevated and ready for attachment to the next person who is to descend. The chain when not in use may be supported in a box, as shown, wound upon a reel or supported in any other manner.

The rotatable shaft 5 is provided within the circular portion of the casing with oppositely-projecting radial arms 16, upon which are slidably mounted weights 17, each of which is of substantially semicircular form. Said weights are loosely connected together and caused to move simultaneously toward and from each other and the shaft 5 by a pair of crossed links or levers 18. These levers cross each other and are formed at their centers with alining openings through which the shaft 5 extends, and their outer ends are formed with slots 19, which loosely engage studs 20, provided adjacent to the ends of the straight sides of the weights 17. These links or levers 18 are disposed in the recessed portions 21 of the weights 17, as clearly shown in the drawings. By mounting the weights in this manner it will be seen that they counterbalance each other and will not drop by gravity when the shaft 5 is rotated at a speed not sufficient to throw them outwardly by centrifugal action. When the

shaft 5 is rotated at a speed fast enough to create a centrifugal force that is greater than the actual weight of the weights 17, they will fly outwardly, so that portions of their peripheries will frictionally engage the inner surface of the cylindrical portion of the casing and serve as a friction-brake to the movement of the chain 7, and hence to the descent of a person upon one of its ends; but when the shaft 5 is rotated slowly the weight will be supported on the shaft and out of contact with the casing, since the links or levers 18 will cause them to counterbalance or support each other. This permits a much smaller load to be lowered by the device than would be possible were the weights so mounted that they would drop by gravity into engagement with the casing when the shaft is rotated at a low rate of speed. The slots 23 in the weight 17, through which the arms 16 project, are tapered outwardly to a slight extent, so that the weights have a slight tilting movement upon them for the purpose of increasing the friction between said weights and the casing. Instead of passing the chain 7 through the casing, as previously described, we may mount it, as shown in Fig. 5 of the drawings, so that the friction offered to its movement will be increased, so as to relieve the friction-brake of a greater portion of the work or permit the latter to be made of lighter construction. As here shown, the chain passes around the under side of the sprocket-wheel, and then up over the friction projections or blocks 24 35 24, and then down between similar friction projections or blocks 25 26 27.

The operation of the device will be readily understood. The belt is attached to the person to be lowered, and as soon as his weight is applied to the chain 7 the latter begins to travel rapidly and to rotate the wheel 6 and shaft 5 with corresponding rapidity, whereby the weights 17 are revolved with the arms 16 and at the same time caused to slide outwardly by centrifugal action, so as to come into frictional engagement with the inner side of the casing. It will be seen that the farther the weights are from the center of rotation the greater the leverage or power required to rotate it and the greater the rapidity of rotation the greater will be the centrifugal action, and hence the higher will be the degree of friction with the casing. Thus the weights serve for two purposes—as an effective brake for regulating the rapidity of rotation of the wheel 6, and thereby the rapidity of travel of the chain 7 over the same, and the descent of the person to the ground. In brief, this apparatus acts most efficiently as

an automatic brake for regulating the descent 60 of light or heavy persons, as the case may be, since the centrifugal tendency of the weights 17 and their friction with the casing will always correspond to the weight of the person. The apparatus is simple in construction, involves no parts likely to get out of order, and all being constructed of metal is exceedingly durable.

Various changes in the form, proportion, and the minor details of construction may be 70 resorted to without departing from the principle or sacrificing any of the advantages of this invention.

Having thus described our invention, what we claim as new, and desire to secure by Letters Patent, is—

1. The combination of a casing having a friction-surface, a wheel revoluble in said casing, a chain engaging said wheel, centrifugally-acting weights revoluble with the wheel, 80 to coact with the friction-surface of the casing to regulate the speed of rotation of the wheel, and a pair of crossed levers also revoluble with the wheel and connected to the weights, for the purpose set forth.

2. The improved fire-escape comprising a casing having a circular portion, a shaft journaled concentrically in said portion, a sprocket-wheel upon said shaft, friction-surfaces arranged in said casing, a chain engaged 90 with said surfaces and adapted to travel on said wheel, a radial arm upon said shaft, and a weight of substantially semicircular form provided with a slot to receive said arm, said slot being tapered outwardly to permit said weight to have an angular movement thereon, whereby a portion of its curved periphery is adapted to frictionally engage the inner wall of said casing, substantially as described.

3. The combination of a casing having a 100 circular portion, a shaft rotatably journaled therein, a chain passed around said sprocket-wheel, oppositely-projecting radial arms upon said shaft, sliding weights upon said arms, and a pair of crossed levers pivotally mounted upon said shaft and having their ends loosely connected to said weights, substantially as described.

In testimony whereof we have hereunto set our hands in presence of two subscribing witnesses.
